LUGGAGE COMPARTMENT FOR RAILWAY CARS

Angus D. McDonald, San Francisco, Calif.

Application December 13, 1938, Serial No. 245,398

9 Claims. (Cl. 105—329)

The present invention relates to a compartment for the hand luggage of passengers in railway cars and like vehicles.

The objects of the invention are to provide one or more compartments in each car in which the hand luggage of passengers can be stored conveniently, either temporarily while passengers are entering and leaving or during the travel of the car; to locate such compartments in the car in positions which are accessible but which take up the least possible space usable for other purposes; to provide access to the compartments from both outside and inside the car, so that luggage can be loaded and unloaded without interference with the entrance and exit of passengers; to provide vertically movable shelves in each compartment actuated by electric power, whereby luggage on the upper shelves can be lowered or raised so as to be equally accessible from the station platform or from the floor of the car; and to provide various safety devices to prevent pilfering or loss from outside or damage to the luggage during the raising or lowering of the shelves.

These and other objects and advantages of the invention will become apparent from the following description, which should be read with the understanding that the form, construction and arrangement of the several parts can be varied, within the limits of the claims hereto appended, without departing from the spirit of the invention as defined in said claims.

A preferred form of the invention, as embodied in a railway passenger car, is illustrated in the accompanying drawings, wherein:

Fig. 1 is a side elevation of a portion of a car, partly broken away and in section to show the principal elements of my luggage compartment.

Fig. 2 is a top plan view, partly in section, of one of the compartments.

Fig. 3 is a diagrammatic floor plan of the end portion of a car showing the preferred location of two luggage compartments therein.

Fig. 4 is a transverse section of one of the compartments.

Fig. 5 is a horizontal sectional detail, enlarged, of a portion of the outer door, taken on the line 5—5 of Fig. 1.

Fig. 6 is a side elevation of the corner of the outer door and its supporting chain shown in Fig. 5.

Fig. 7 is a broken plan of one end portion of one of the shelves, showing its supporting brackets and chains.

Fig. 8 is an elevation of the end portion of the shelf shown in Fig. 7.

Fig. 9 is a plan of the motor clutch and drive mechanism for operating one of the shelves.

Figs. 10 and 11 are respectively an end and side elevation of the same drive mechanism shown in Fig. 9.

Fig. 12 is a diagram of the electrical connections for operating and controlling the shelves and the outer door.

In Figs. 1, 2 and 4 of the drawings, certain parts have been omitted, and other parts shown in conventionalized form, for the sake of clearness and to avoid confusion on account of the necessarily small scale. Thus the chains which support the movable shelves and door are shown as single lines, and the bearings and supports for the sprocket wheels of said chains have been omitted. The specific construction of the omitted and conventionalized parts form no part of the invention.

The preferred positions in the car for my luggage compartments are best shown in the floor plan, Fig. 3, and as designated by the reference numerals 14, are at the ends of the car, just inside the end wall 15 which separates the body of the car from the vestibule platform 16. When this position is used, there may be four compartments in each car, two at each end on either side of the center aisle 17. The compartments 14 are immediately inside the side walls 18 of the car, between the end wall 15 and a transverse wall or bulkhead 19 at the end of the passenger compartment 20.

Each compartment extends from the floor 21 of the car to a ceiling 22 somewhat below the main ceiling 23, as shown in Fig. 4, and is separated from the aisle 17 by a vertical partition 24, which has a full-height door 25, shown only in Fig. 2, opening into the compartment from the aisle 17. The door 25 may be of any suitable type, and is indicated in said Fig. 2 as a multiple section folding hinged door. Each compartment also has an exterior door 26, Figs. 1, 2 and 4, opening through the side wall 18 of the car into the lower portion of the compartment. The outside door 26 is preferably of the vertical sliding type, and is mechanically and electrically operated and controlled by mechanism to be described hereinafter.

The compartment 14 is provided with a plurality of vertically movable shelves, two such shelves, 27 and 28, being shown in the drawings. The shelves are provided at each end with two suitable guide lugs 29, Figs. 2 and 7, which slide on vertical fixed rails 30 in the form of angle bars. Vertical fixed partitions 31 extend between

the rails 30 at the ends of the shelves. The shelves are hung from, and moved by, vertical chains operating in the spaces between the partitions 31 and the end walls of the compartment.

5 The partitions 31 serve to keep the luggage on the shelves from coming into contact with the operating chains.

The mechanism for supporting and moving the lower shelf 27 will now be described. A pair of 10 horizontal longitudinal rails 32 extend under the shelf from end to end, and their projecting ends are forked, as shown in Fig. 7. The extreme end portions of said rails are attached to vertical endless chains 33, which run over idler sprockets 15 34, Figs. 1 and 4, beneath the floor, and over drive sprockets above the compartment ceiling. At the left hand end of the shelf shown in Figs. 7 and 8, the rails or brackets 32 are attached to the outer runs of the chains 33, their inner runs 20 passing freely through said brackets. At the right hand end of the shelf the brackets are shorter, as indicated in Fig. 1, and are attached to the inner runs of the chains. The drive sprockets 35, at the right hand end of the compartment, 25 as viewed in Figs. 1 and 2, are secured upon a horizontal shaft 36, and the left hand drive sprockets 37 are secured upon a horizontal shaft 38. The two shafts 36 and 38 turn in the same direction to move the shelf, and are connected 30 together by a horizontal chain 39 running over sprockets 40 secured upon said shafts. The shaft 38 is the drive shaft, and is driven by a motor 41 through a gear and clutch mechanism designated as a whole as 42 and shown in detail in 35 Figs. 9, 10 and 11.

The motor 41 drives a worm wheel 43 rotatably mounted on the sprocket shaft 38. A clutch member 44 is slideable but not rotatable on said sprocket shaft, and has notches 45 engaging pins 46 projecting from the worm wheel 43. A spring 47 holds the clutch in engagement, and a forked hand lever 48, having lugs 49 riding in a groove 50, disengages the clutch. The lower end or handle of the lever 48 extends down through the 45 ceiling 22 of the compartment, where it can be reached from within.

The purpose of the clutch mechanism is to disconnect the shelf and its supporting chains from the motor, so that said shelf can be raised or lowered by hand, if necessary, in the event of failure of the electrical system of the car, which supplies power to the motor 41. It is intended, when the compartment is empty, and luggage is to be loaded from outside, i. e. when the car is 50 taking on passengers, that the shelves will first be lowered to the bottom of the compartment. Then the upper shelf 28 is loaded through the outside door 26, and raised to its upper position, as shown in Fig. 4. The lower shelf 27 is then 55 loaded through said outside door, and raised to its upper position. Finally the bottom of the compartment is filled with luggage through said outside door. The luggage can then either be left in the compartment during the car's journey, 60 or such of it as may be needed by the passengers can be taken out through the inside door 25 without moving the shelves. The reverse process is followed when the car is discharging passengers and luggage is unloaded onto the station 65 70 platform.

If the electric power supply should fail at the time the car is ready for loading, it would be necessary to raise the shelves by hand, before the luggage is placed upon them, so that said 75 luggage could be passed through the lower por-

tion of the compartment from outside and some of it placed on the shelves by a porter in the car. In such an emergency, the porter can disengage the clutches and raise the shelves by hand. In order to prevent the shelves from dropping, even when loaded, when the clutches are disengaged, each sprocket drive shaft is provided with a safety pawl interlocked with the clutch release lever, as described in the following paragraph.

A ratchet wheel 51, Figs. 9, 10 and 11, is secured 10 upon the sprocket shaft 38, and may be engaged by a pawl 52 formed as the vertical arm of a bell crank lever, whose horizontal arm 53 has a lug 54 projecting through a slot in the ceiling 22 and resting upon a horizontally movable lever 55 15 below said ceiling. The lever 55 has a lug 56 engaging the clutch lever 48, so that said clutch lever 48 cannot be moved to release the clutch unless the interlock lever 55 is first moved horizontally, which movement allows the arm 53 to 20 drop and the pawl 52 to engage the ratchet wheel 51, thereby preventing the shaft 38 from turning in a direction to drop the shelf.

The upper shelf 28, Figs. 1, 2 and 4, is supported and raised and lowered by mechanism similar 25 to that described above. The horizontal supporting rails 57 of said shelf are attached to vertical endless chains 58 running over lower idler sprockets 59 and upper drive sprockets 60. The drive sprockets 60 at the left, as viewed in Figs. 1 and 30 2, are secured upon a horizontal shaft 61, and those at the right upon a horizontal shaft 62, the latter being the drive shaft. The shafts 61 and 62 are connected together by a horizontal chain 35 63 running over sprockets 64. The drive shaft 62 is driven by an electric motor 65 through a gear and clutch mechanism 66 similar to the mechanism 42 described above, and provided with a similar safety catch interlocked with the clutch lever. Thus each shelf is operated by its own independent mechanism.

The outside door 26 opens by sliding upwardly between the outer and inner sheathing of the side wall 18, as indicated in Figs. 2 and 4, and is preferably operated by mechanism similar to that 45 which operates the shelves. The door 26 is slidably mounted in guide members 67, Fig. 5, secured to the outer and inner sheathing of the wall 18, and has forked brackets, one of which is shown at 68, extending into the space 69 between said 50 sheathing. The brackets 68 are attached to vertical endless chains 70, Figs. 5 and 6, running over lower idler sprockets 71, Figs. 1 and 4, and upper drive sprockets 72, secured upon shafts 73, which are connected together by a horizontal chain 74. The right hand shaft 73, as viewed in Figs. 1 and 2, is the drive shaft, and is driven by an electric motor 75 through a gear and clutch mechanism 76 similar to that described above for operating the shelves, as shown in Figs. 9, 10 and 11.

The shelves 27 and 28 may be raised manually from inside the car, as previously described, when their respective clutches are disengaged. In order to provide for manual operation of the shelves and outside door, from outside the car, if such should be necessary, the shafts upon which the idler sprockets 34, 59 and 71 are mounted may be provided with squared ends 34a, 59a, 71a, as shown at the left hand side of Fig. 1, which are accessible for a removable crank (not shown) 70 through properly aligned holes in the side wall 18 of the car. Thus by fitting a crank upon any of said squared shafts, the shelf or door connected therewith can be operated by hand from outside, after its clutch has been released.

The three motors 41, 65 and 75, operating respectively the lower shelf 27, upper shelf 28, and outside door 26, are separately controlled by an electric control system, which also includes certain electrical interlocking features for the purpose of preventing damage to the luggage through careless operation of the shelves and door. The control system is shown in Figs. 1 and 12, and is operated mainly by switches positioned in the side wall of the car near the outside compartment door 26, with certain safety and emergency switches positioned inside the car near the inside compartment door.

The power line wires 71, Fig. 12, connected with the electric system of the car, lead first to a main switch 78 positioned inside the car, which cuts out the entire system to prevent unauthorized use. One line wire 79 leads from the main switch 78 to a manual selector switch 80 positioned outside, from which three wires 81, 82, 83 lead respectively to three manual motor control switches 84, 85, 86, also positioned outside. Each of the latter is a three-way switch providing for starting its connected motor in either direction and for stopping it. Thus the switch 84 for example, which controls the door motor 75, has three buttons or positions, one for raising the door, one for lowering it, and one for stopping the motor.

Actual control of the motor connections is accomplished by electrically operated starting and reversing relays, of well known type, indicated at 87, 88 and 89, for the three motors 75, 41 and 65 respectively. The manual control switches 84, 85, and 86 are connected with said relays respectively by wires 90, 91, 92, and the other line wire 79a from the main switch 78 branches and leads to the starting and reversing relays through wires 93, 94, 95. The control circuits to the starting and reversing relays run through separate manual cut out switches 96, 97, 98 positioned inside the car, so that any motor can be individually cut out for repairs without cutting out the others. A manual two-way switch or button 99 is provided inside the car for closing the outside door in case it should be inadvertently left open, and is connected by a wire 100 in parallel with the down or closing contact of the door switch 84.

Each movable part, i.e. the door and each of the two shelves, is provided with limit or automatic stop switches to turn off the motor at the end of the permissible movement. The lower and upper door limit switches 101, 102 are positioned between the outer and inner sheaths of the side wall of the car and are engaged and operated by one of the extending hanger brackets 68 of the door, as indicated in Fig. 1. The limit switches 101, 102 are connected with the door motor starting and reversing relay 87 by wires 103 and 104, Fig. 12. The limit switches 105, 106 for the lower shelf 27, and 107, 108 for the upper shelf 28, are positioned in the chain space at one end of the compartment, and are operated by the projecting hangers 32 and 57 of the respective shelves 27 and 28. The limit switches 105, 106 are connected with the lower shelf motor starting relay 88 by respective wires 109, 110, and the limit switches 107, 108 are connected with the upper shelf motor starting relay 89 by respective wires 111, 112.

Electric interlocks are provided, to prevent operation of either shelf when the outside door is closed, and to prevent raising the lower shelf when the upper shelf is down, or lowering the upper shelf when the lower shelf is up. The interlocks comprise simple two-way switches op-

erated by the door and the shelves and connected with the motor starting relays. A switch 113 is positioned to be engaged and closed by the top of the door 26 when the latter is in open position, and is connected by wires 114 and 115 with the starting relays 88 and 89 of both shelf motors, in such a manner that said relays cannot operate to start their respective motors except when the said interlock switch is closed.

A similar interlock switch 116 is positioned to be engaged and closed by the lower shelf 27 when said shelf is in its lowest position, and is connected by wires 117 with the starting relay 89 of the upper shelf motor 65, so that the upper shelf cannot be lowered except when the lower shelf is all the way down. Similarly, an interlock switch 118 is positioned to be closed by the upper shelf 28 when said shelf is in its uppermost position, and is connected by wires 119 with the starting relay 88 of the lower shelf motor 41, so that said lower shelf cannot be raised except when the upper shelf is all the way up. The manual selector switch 80 also provides a feature of safety by preventing simultaneous operation of more than one moving element.

The operation of the apparatus may be restated briefly as follows: when the car is about to take on passengers at a station, the car porter or some other train attendant turns on the main switch 78. The individual motor cut out switches 96, 97, 98 are normally closed. The station porter first turns the selector switch 80 to its door operating position, and then operates the door switch 84 to open the outside compartment door 26. He then, by successive manipulation of the selector 80 and the shelf switches 85, 86, lowers both shelves 27, 28 to their lowest positions upon the floor of the compartment.

Loading of luggage through the outside door 26 then begins, and when the upper shelf 28 is filled with luggage, it is raised, by manipulation of the selector 80 and the shelf switch 86, to its uppermost position. Luggage is then placed on the lower shelf 27, and that shelf is also raised by manipulation of the selector 80 and the shelf switch 85. The last luggage is then placed on the floor of the compartment, and the outside door 26 is closed. The luggage may either be left in the compartment, or removed therefrom through the inside door 25 and taken to the passengers' seats. Before the car reaches its destination, all luggage removed from the compartment during the journey, and not carried by passengers, is replaced in it by the car porter, and the station porter removes it through the outside door 26 while the passengers are alighting, following the reverse procedure from that described above for loading.

The various safety features prevent possible loss of or damage to the luggage. The car porter can close the outside door 26 by means of the inside switch 99 if it has been left open inadvertently by the station porter. The car porter also keeps the main switch 78 off except when the car is at a station where luggage is to be loaded or unloaded by a station porter or other authorized attendant. The interlock switches 113, 116, 118 prevent lowering of the shelves except when the outside door is open, so that the attendant can see that the floor space beneath the lower shelf is empty before he begins to lower it, and said interlock switches also prevent crowding the two shelves together. The releasable clutches and their associated safety pawls

permit the door and shelves to be raised by hand, if the electric power supply fails, but prevent the shelves from dropping.

It will be seen from the foregoing description that the luggage is loaded and unloaded through a door entirely separate from the door and passageway through which passengers embark or alight, so that the movement of the passengers is not interfered with in any way, and the usual delay caused by loading and unloading luggage is eliminated. Moreover, the luggage, or such of it as is not wanted by the passengers during the journey, is stored in a safe place, out of the passengers' way.

15 I claim:

1. In a passenger vehicle having an outside wall, a luggage compartment within the vehicle, a door in said wall opening into the lower portion of said compartment, and the top of said compartment being above the top of said door, a shelf in said compartment, said shelf being vertically movable to raise luggage from the lower portion to the upper portion of said compartment, and said compartment having an opening into it from the interior of the vehicle.

2. In a passenger vehicle having an outside wall, a luggage compartment within the vehicle, a door in said wall opening into the lower portion of said compartment, a plurality of shelves in said compartment, said shelves being independently movable vertically to raise luggage from the lower portion to the upper portion of said compartment, and said compartment having an opening into it from the interior of the vehicle.

3. In a passenger vehicle having an outside wall, a luggage compartment within the vehicle, a door in said wall opening into the lower portion of said compartment, a shelf in said compartment, said shelf being vertically movable to raise luggage above the top of said door, and said compartment having an opening into both its lower and upper portion from the interior of the vehicle.

45 4. In a passenger vehicle having an outside wall, a floor and a ceiling, a luggage compartment within the vehicle extending approximately from the floor to the ceiling, a door opening into said compartment from the interior of the vehicle, said door being approximately the full height of the compartment, a second door in said outside wall opening into said compartment, said outside door being of less height than the inside door, and a shelf in said compartment, said shelf being vertically movable to raise luggage to a position above the top of said outside door.

5. In a luggage compartment for passenger

vehicles, an enclosure within the vehicle having an opening for the entrance and discharge of luggage, a plurality of independently movable shelves within said enclosure, power driven mechanism for raising and lowering said shelves, manual control means for selectively starting the movement of said shelves, and automatic control means for stopping said shelves at their respective limits of movement.

6. In a luggage compartment for passenger vehicles, an enclosure within the vehicle having an opening for the entrance and discharge of luggage, a plurality of independently movable shelves within said enclosure, power driven mechanism for raising and lowering said shelves, manual control means for selectively starting the movement of said shelves, and interlocking control devices for preventing simultaneous movement of more than one of said shelves.

7. In a luggage compartment for passenger vehicles, an enclosure within the vehicle having an opening for the entrance and discharge of luggage, a plurality of vertically movable shelves within said enclosure, a plurality of suspension members by which each shelf is supported, and independent means for raising and lowering the suspension members of each shelf, whereby said shelves may be moved vertically independently of each other.

8. In a luggage compartment for passenger vehicles, an inclosure within the vehicle having an opening for the entrance and discharge of luggage, a vertically movable shelf within said enclosure, vertical guides upon which said shelf moves, a plurality of vertical endless chains, each chain having one of its runs attached to said shelf, there being two chains adjacent one side of said shelf and two chains adjacent its opposite side, a horizontal shaft having fixed upon it two sprockets over which run the two chains at one side of the shelf, a second horizontal shaft having two sprockets over which run the chains at the other side of the shelf, a third sprocket on each shaft, a horizontal endless chain connecting said third sprockets, and power means for rotating one of said shafts.

9. In a luggage compartment for passenger vehicles, an enclosure within the vehicle having an opening for the entrance and discharge of luggage, a plurality of vertically movable shelves within said enclosure, independently movable supporting members for each shelf, and means for selectively moving said supporting members whereby said shelves may be raised and lowered independently.

ANGUS D. McDONALD.
